UNITED STATES PATENT OFFICE

CHARLES A. BAY, OF MORRISTOWN, NEW JERSEY

EXTENSION LADDER

Application filed May 29, 1930. Serial No. 457,010.

This invention relates to improvements in extension ladders and more particularly to extension ladders and supporting and controlling means associated therewith.

For certain purposes, such, for example, as the inspection and care of incandescent lamps mounted for street lighting on fixed brackets at a considerable height, it is desirable to have a portable extension ladder whereby such inspection and care is facilitated. Heretofore various means for meeting such requirements have been proposed, but such proposed devices have in general been undesirable and even impracticable, due, for example, to cumbersomeness, complication of structure, or lack of suitability for transportation. The main object of the present invention is to provide improved extension ladder apparatus. Further objects are to provide extension ladder apparatus which can readily be applied to a vehicle such as a motor truck; an improved combined motor truck and extension ladder; and safety devices for extension ladder apparatus. Other features of the invention relate to the construction and arrangement of parts whereby the desired results are obtained.

In the accompanying drawings illustrating the preferred form of the invention, Fig. 1 is a side elevation of an automobile equipped with the improved extension ladder; Fig. 2 is a view illustrating the ladder in raised and extended condition; Fig. 3 is a perspective view of the upper end of the longitudinally shiftable ladder section; Fig. 4 is a perspective view of the upper end of the main ladder section; Fig. 5 is a fragmentary view, partly in section, of the lower end of the ladder when the shiftable section is in lowered or retracted position; Fig. 6 is a fragmentary elevation, partly in section, illustrating the relation of the main ladder section to the supporting frame and platform; Fig. 7 is a section taken just above the diagonal connectors at the base of the supporting frame; Fig. 8 is a sectional view of one of the devices with which the latching bolts on the main ladder section cooperate; Fig. 9 is a diagram of an electric circuit containing signalling means to indicate when

both of the latching bolts are in effective position; Fig. 10 is a perspective of a bolt guiding device mounted on the lower end of one side of the main ladder section; Fig. 11 is a perspective view of another bolt guide; Fig. 12 is a fragmentary vertical section taken through the pivotal axis of the main ladder section when the ladder is in condition for transportation; Fig. 13 is a view of the lower end of the ladder in collapsed condition, certain parts being broken away; Fig. 14 is a detail view illustrating parts of the connections at the pivotal support for the ladder; Fig. 15 is a view illustrating parts of the connections between rungs and longitudinal connectors; Fig. 16 is a fragmentary view, partly in section, illustrating means for holding the ladder in position for transportation; and Fig. 17 is a top view of the structure shown in Fig. 16.

The improved apparatus, as illustrated in the drawings, includes a base frame adapted for easy installation in the body of an automobile truck, a main ladder section pivoted on said frame to swing about an axis transverse with respect to the body of the truck, means for latching the rear end of the ladder to the base when the forward end of the ladder is swung upwardly to its raised position, means to indicate when such latching means is effective, a movable ladder section 80 85 90 95 100 105 110 115 120 125 130 135 140 145 150 155 160 165 170 175 180 185 190 195 200 205 210 215 220 225 At each side of the frame a member 6 extends upwardly and rearwardly from the forward end of the corresponding side member 3 and a member 7 extends upwardly and forwardly from the rearward end of such member 3. Such members 6 and 7 at each side of the frame are connected with the base members 3 and 4 by means including corner plates 8 and their inclination is such that their upper ends are adjacent and can easily be connected by a plate 9 which is utilized to support the extension ladder at one side.

The side frames formed by the members 6 and 7 at opposite sides of the main frame are inclined toward each other to provide better support against sidewise stresses exerted by the extension ladder and the main frame is braced at each side by a cross member 10 connected with the corresponding members 6 and 7 at points intermediate their ends and at the front by diagonal braces 11 and horizontal members 12 connected with a generally central plate 13 and with the members 6.

The rear side of the frame 1 is left open between the members 7 to receive one end of the extension ladder and the members 6 are made longer than the members 7 so as to position the plate 9 to the rear of the middle points of the side members 3 and thereby provide more effective support for a ladder which is inclined upwardly and forwardly when in use. As illustrated in the drawings, the supporting frame may conveniently be built of metal angles and suitable connections.

It is of importance to provide not only a frame which can readily be inserted in a vehicle body but also suitable means for connecting it with said body. According to the illustrative form of the apparatus, this result is attained by placing planks or joists 14 on the floor 15 of the body 2 to receive thereon the sides of the base of the supporting frame and by securing the frame to the floor 15 by suitable means such as hooks 16 engaging the front end member 4 at points adjacent to the inner edges of the joists and passing through the floor 15, and bolts 17 passing downwardly through the corner plates 5 at the rear of the frame. The hooks 16 are tightened and held in position by nuts 18 threaded on the lower ends of the hooks and separated from the floor 15 by suitable washers. As will be brought out more clearly hereinafter, the tendency to lift at the rear end of the frame is greater than at the front end. As a result of this condition, it is found desirable to reinforce the floor 15 by a metal strip 19 engaging the lower side thereof. The bolts 17 pass through said strip and are engaged by nuts 20 which are tightened to draw the parts firmly together.

The extension ladder comprises a main or lower section 21 pivotally supported by the plates 9 at the top of the main frame, and a similar shiftable section 21a slidably mounted

in said main portion 21. When the ladder is collapsed, the sections are in what may be called nested relation. The section 21, taken as a whole, is triangular in cross section and includes a part which in itself is a complete ladder comprising side-pieces 22 and cross-pieces or rungs 23, and a part of V-shaped cross section comprising three longitudinal members 24 and cross-pieces or rungs 25 extending from one of said members 24 to the other two which are adjacent to and are secured to the side pieces 22.

The side-pieces 22 and the adjacent side-pieces 24, although at substantially the same distance apart throughout their lengths are in angular relation with respect to each other and are secured together at points, corresponding with the location of the rungs 23, by means including bent plates 27 engaging the outer faces of side-pieces 22 and 24, correspondingly bent plates 28 engaging the inner faces of side-pieces 22 and 24, rod 29, and nuts 30 threaded on the ends of said rods.

As shown in Fig. 13, the rods 29 extend through openings 31 and 32 (see Fig. 15) in the plates 27 and 28, respectively, through openings 33 in the side-pieces 22, and axially through the rungs 23. The plates 27 and 28 are connected with the corresponding members 24 by suitable means such as bolts 34 and nuts 35. The rungs 23 should be held against turning and in the illustrated embodiment of the invention this result is attained by providing each of such rungs at each of its ends with a pin 36 to enter a corresponding opening 37 in the corresponding plate 28. Preferably the rungs are made of hard fibre.

The rungs 25 of the V-portion are held in position between the longitudinal members 24 by rods 38 extending axially through the rungs and nuts 39 threaded on the ends of the rods. The rods 38 also pass through plates similar to plates 27 and 28 which are bolted at their other ends to the side-pieces 22a. Ordinarily no provision to prevent turning of the rungs 25 is necessary.

The ladder section 21a is constructed in the same general manner as the ladder section 21 and, for convenience, the parts of the section 21a corresponding with parts of the section 21 will be designated by the same reference numerals but with the letter *a* associated therewith. The main difference between the sections or ladders 21 and 21a resides in the smaller cross section of the section 21a which enables it to enter the section 21. To prevent interference with the sliding of the section 21a in the section 21, the intermediate member 24a is provided at its outer edges with strips 40 which prevent engagement of the corresponding rod ends and nuts with the rungs 25. In this connection, it should be noted (see Figs. 12 and 13) that the construction of the ladder sections 21

and 21a at the sides where the rungs 23 and 23a are located is such as to avoid any interference with the sliding of the section 21a in the section 21. The rungs 23 can be engaged only by straight sides of the members 22a and the rungs 25 can be engaged only by straight sides of the members 24a in addition to the strips 40.

The main ladder section or ladder 21 may be pivotally mounted on the plates 9 of the supporting frame in a manner shown most clearly in Fig. 12. A hollow rung 42 of metal, provided at its ends with plates or flanges 43, is interposed between the side pieces 22 at the proper location for the pivotal axis and the plates 43 which are integral with the rung 42 are secured to the members 22 by bolts 44 passing through openings 45 in the plates 43, through the members 22, and through openings 46 in plates 47 at the outer sides of the members 22, the ends of the bolts being engaged by nuts 48. Preferably the plates 43 and 47 extend beyond the edges of the members 22 towards the members 24 and are bent so as to engage the same at the sides and are fastened with a bolt similar to 44. Blocks or spacers 49 are interposed between the plates 47 and the plates 9 of the supporting frame and the pivotal connection is completed by a bolt 50 passing through the plates 9, the blocks 49, the plates 43 and 47, the side pieces 22 and the hollow rung 42. The bolt is secured in position by means of nut 51 threaded on the bolt and engaging the outer side of a washer.

The bolt 50, which constitutes the pivot for the ladder section 21, is located near the lower or rear edges of the members 22 and at such a position longitudinally thereof that the rear or lower end of the ladder section may be swung into the supporting frame. In order to obtain a sufficient effective length for the ladder section 21 and for other reasons, it is generally desirable to have the part of the section or portion 21 at the front of the pivot of greater length than the part at the rear of the pivot.

The overbalancing to the front of the pivot resulting from the position of the pivot along the side-pieces 22 and from the shiftable ladder section 21a mounted in the main portion, tends to cause the ladder to swing forwardly; and when the ladder is not in use it is supported by suitable means at the front of the truck. In order that the side-pieces 22 may be of great strength without undue increase in weight, they are of considerable depth adjacent to the pivot but decrease in depth toward their ends.

Referring to Figs. 1 and 16, the truck is provided at opposite sides with uprights 53 which may rest on the running boards and be attached at a higher level with the front of a driver's cab, and a cross member or beam 54 connecting the upper ends of said up-

rights. The intermediate longitudinal member 24 of the main ladder section 21 seats itself in a notch at the upper side of a block 55 supported by the cross member 54. As here shown the block or member is supported in a socket member 56a secured to the cross member 54 at the front side thereof.

Although the weight of the ladder tends to hold it in the seat in the block 55, it is desirable to provide means for preventing the ladder from jumping up from the seat. For this purpose, there are provided at the rear side of the cross member 54 two levers 56 pivoted at the same level on pivots 57 and connected by a link 58 pivoted to one of the levers 56 at a point below the corresponding pivot 57 and to the other lever at a point above the corresponding pivot 57, so that the levers swing outwardly and inwardly together. The upper ends of the levers 56 are bent inwardly and are provided at their inner sides with flat portions or plates 59 which are so inclined as to engage and lie along the inner surfaces of the intermediate member 24a, as indicated in Fig. 16.

The levers 56 are yieldably urged together to engage the ladder and hold it down on the seat in the block 55. As here shown, a link 60 is pivotally connected at one end with a yoke 61 embracing one of the levers 56 and connected therewith by a pivot 62, and at the other end with a handle 63 extending from the link at a right angle. At an intermediate point the link passes through a bracket 64 fixed on the beam 54 and the urging of the levers 56 to clamping position is effected by means of a spring 65 interposed between the yoke 61 and the bracket 64. The yoke 61 may be drawn outwardly by means of the handle 63 to release the ladder and then turned to permit the handle 63 to rest against the outer side of the corresponding upright 53 and prevent return of the link under the urging of the spring. Accidental opening of the levers 56 and consequent release of the ladder is prevented by engagement of the link with a bracket 65a secured to the cross member 54, the handle 63 being in its Fig. 16 position. Also the bracket 65a keeps the handle 63 from slipping along the upright when in its locking position.

It would be undesirable to start the truck when the ladder is raised or even when it is unlocked. To guard against starting under such conditions, one of the arms or levers 56 is connected by means of a link 66 with an arm 67 of a switch 68 in a controlling circuit such as an ignition circuit, so that when the arms 56 are thrown apart the circuit is broken at that point and when they are returned to holding position the circuit is closed at that point.

When the ladder is to be raised, the handle 63 is drawn out to release the ladder and placed in engagement with the outer face of

the corresponding upright to prevent return of the holding members to holding position. The forward part of the ladder is then swung upwardly as by pulling down on the rear 5 part thereof and the rear end of the main section 21 is swung into the main frame and secured in proper position therein by suitable means which will now be described.

Mounted at the lower end of the main 10 ladder section 21 and at the outer side of each member 22 near the corresponding member 24, is a latching bolt 70 of which the lower end projects through an opening 71 in a flange 72 or the like projecting from the bottom 15 of a socket or tip 73 receiving the lower ends of adjacent side-pieces 22 and 24 and secured thereto in any suitable manner. Each bolt is also guided by devices 74 (Fig. 11), each comprising a central plate portion 20 to be secured to the corresponding members 22 and 24 in any suitable manner, as by means of bolts or screws passing through holes 75, and at each side of such central portion with split eyes 76 to receive the bolt, 25 such eyes being closed to the desired extent by bolts 77 and nuts threaded thereon.

Each bolt 70 is urged downwardly by suitable means, such as a spring 78 surrounding the bolt and interposed between the lower 30 side of one of said devices 74 and a collar 79. The downward movement of each of the bolts may be limited in any suitable manner, as by means of a stop 80 located thereon in a position to engage the member or plate 72, 35 and lifting of the bolt may conveniently be effected by means of a flexible member or rope 81 extending from a fixed connection with the ladder portion 21 downwardly and through an eye 82 in the upper end of the bolt, upwardly and over a pulley 83 fixed on the ladder portion or section 21, and then downwardly, the end of the rope being provided with a suitable handle, such as a ring 84.

40 When the lower end of the ladder is swung downwardly and forwardly into the main frame, the lower ends of the bolts 70 ride up on the downwardly inclined forward ends of fixed plates 85 and along the upper surfaces 45 of the plates until they drop into suitably positioned openings 86 in said plates. In some cases it may be necessary to pull down on the rings 84 to lift the bolts 70 high enough to ride over the plates 85. Support for these 50 plates is provided by a cross member 87 attached at opposite ends to the posts or members 7 at the rear of the main frame and also by diagonal members 88 supported at their rear ends on the member 87 and at their forward ends on the cross member 4 at the base 55 of the main frame. At the crossing of the members 88, there is secured to said members at the lower sides thereof, a plate 89 having a downwardly inclined rear end so 60 that the lower end of the intermediate mem-

ber 24 will readily pass over the top thereof into the V-shaped opening between the members 88. In this connection, it should be noted that immediately to the front of the plates 85 the diagonals 88 are turned upwardly so that the lower end of the intermediate member 24, while passing freely over the cross member 87, will rest on or come close to the upper surface of the plate 89 and therefore will be sure to enter said V-shaped opening between the members 88 (see Fig. 7).

To support the upper ladder section 21a on the lower section 21 in any desired position, the upper section is provided at opposite sides with devices 90, here shown in the form of hooks pivoted on the section 21a and adapted to hook over rungs 23 on the main ladder section 21. The upper ends of the hooks are shaped so as to be cammed back by the rungs 23 during the upward movement of the ladder portion. If the hooks are raised just above a rung 23 and then lowered, they will engage the rung and hold the ladder section 21a in raised position; but if the hooks are raised high enough above a rung to permit the pivoted fingers 91 associated with the hooks to pass above the rung and the ladder section 21a is then lowered, the fingers will close the hooks and prevent their engagement with any of said rungs 23 during the downward movement of the ladder section 21a. For convenience the hooks 90 are pivoted to the members 22a at the positions where the next to lowest rung 23a would ordinarily be positioned. The hooks and associated parts may be substantially the same as devices heretofore in use for such purposes.

The raising and lowering of the ladder section 21a may conveniently be effected by means of flexible connectors or ropes 92 fixedly attached to the members 22 near their upper ends and looped downwardly around pulleys 93 attached to the members 22a near their lower ends, and upwardly over pulleys 94 attached to the members 22 at points spaced downwardly to some extent from their upper ends. The ropes 92 after being looped over the pulleys 94 and extended downwardly far enough to avoid interference with the lowering of the ladder section 21a, are preferably combined at a convenient point into a single member 95 for convenience in handling.

To add to the safety of operation, provision is made of means to indicate whether the bolts 70 are securely latched to the plates 85. As here shown, such means include switches 96 mounted below the plates 85 so as to be closed by the bolts 70 when they pass downwardly into the openings 86 in such plates, and a circuit 97 containing the switches 96, a suitable current source 98 and lamps 99 mounted on the rear faces of legs 7 at the rear of the main frame. Preferably 130

this circuit is grounded. The circuit will be closed only when both bolts 70 are in latching position and at the time both lamps 99 will be lighted.

- 5 As shown in Fig. 8, each switch 96 is mounted in a box 100 at the lower side of the corresponding plate 85 and includes a U-shaped member 101 having a short leg secured on the upper side of a plate 102 of insulating material and a longer upper leg to be pressed down by the corresponding bolt 70 into engagement with another contact 103. The plate 102 of insulating material is suspended from the plate 85 in a suitable manner and the two contacts 101 and 103 are connected through the plate 102 with the ends of conductors forming part of the circuit 97. Preferably the upper leg of each contact 101 is provided with a block 104 of insulating material to protect it against wear which would otherwise result from engagement by the bolt 70.

Recapitulating briefly, the operation is as follows: During transportation of the apparatus to the desired location, the parts are located as indicated in Fig. 1. When the vehicle has been placed in the proper position, the handle 63 is pulled to the right to separate the clamping levers 56 and release the ladder sections 21 and 21a at the forward part of the vehicle or truck, and is then turned into position to engage the outer side of the corresponding upright 53 and prevent return of the link 60 under the action of the spring 65 and the consequent return of the clamping levers to latching position. The movement of the handle 63 to the right also acts to open the switch 68 and thereby prevent starting of the motor of the truck.

40 Then the ladder structure is swung about the pivot or bolt 50 to raise the forward part and depress the rearward part until the latching bolts 70 ride over the fixed plates 85 and enter the openings 86, thus securing the main section 21 in position for use. Proper latching of the bolts 70 to the plates results in closing both of the switches 96 and lighting both of the lamps 99. It will be seen that lighting of these lamps indicates effective latching action by the bolts 70.

At this time, the hooks 90 on the shiftable section 21a are in engagement with the rung 23 which is the third from the bottom, and the lower ends of the two ladder sections 21 and 21a are in adjacent positions. The shiftable ladder section 21a may then be raised to the desired height by means of the flexible members or ropes 92 and 95. In such upward movement, the hooks 90 ride across the successive rungs 23 and, if the section 21a is raised no higher the hooks will engage that rung and support the ladder portion in such raised position. The ladder section 21a can, however, be lowered at any time by raising it high enough to cause the fingers 91 to be en-

gaged by the rungs 23 and close the hooks 90 to prevent the latter from engaging any of said rungs. When the use of the ladder is completed, the various steps are reversed and the parts restored to their Fig. 1 positions for transportation to other points.

Obviously the extension ladder may be made up of more than two ladder sections. It should also be understood that various changes may be made in the construction and arrangement of parts and that certain parts may be used without others without departing from the spirit and scope of the invention.

I claim:

1. In apparatus of the class described, the combination with a supporting frame, of a ladder pivoted thereon, ladder latching means to hold said ladder in raised position, and means controlled by said ladder latching means to indicate when latching is effected.

2. In apparatus of the class described, the combination with supporting means, of a ladder pivoted thereon, and means for latching said ladder in raised position including a downwardly urged member mounted on said ladder and movable longitudinally thereof, and a fixed plate having an opening to receive said downwardly urged member and having a portion of its upper surface inclined so that when the ladder is swung to raised position the downwardly urged member will ride up the inclined portion of the upper surface of said plate and enter said opening.

3. In apparatus of the class described, the combination with supporting means, of a ladder pivoted thereon, longitudinally movable latches mounted on said ladder at opposite sides thereof, stationary members having openings to receive said latches, and indicating means including an electric circuit having switches therein in position to be engaged by said latches when the latter move to latching position.

4. In apparatus of the class described, the combination with supporting means, of a ladder pivoted thereon, latching devices for each side of the ladder, and a circuit including a light on each side of said supporting means and two switches in series in said circuit and controllable by the corresponding latching devices.

5. In apparatus of the class described, the combination with a motor truck having a controlling circuit, of a switch in said circuit, a ladder pivoted on said truck, means for holding said ladder in lowered position, and means operable by such holding means for opening said switch when such holding means is released.

6. In a ladder, the combination of side pieces, hollow rungs having pins projecting longitudinally of said rungs and from the material surrounding the passages through

said rungs, rods extending through said rungs and said side pieces, and plates interposed between the ends of said rungs and said side pieces, said plates having openings 5 to receive said rods and openings to receive said pins.

7. In a ladder structure, the combination with a ladder proper comprising two side pieces and rungs connecting the same; a rear 10 portion comprising longitudinal pieces adjacent to said side pieces, an intermediate longitudinal piece spaced rearwardly from the ladder proper and two series of rungs each series connecting said intermediate longitudinal piece with the other longitudinal pieces, respectively; and means for securing 15 said side pieces and the corresponding longitudinal pieces together.
